UNITED STATES PATENT OFFICE.

ALFRED C. URBAN, OF BUXTON, IOWA, ASSIGNOR OF ONE-HALF TO
NATHAN P. HERRINGTON AND ONE-FOURTH TO ERIC F. BROWN,
OF BUXTON, IOWA.

MINE-DOOR.

No. 808,125.

Specification of Letters Patent.

Patented Dec. 26, 1905.

Application filed May 12, 1905. Serial No. 260,112.

To all whom it may concern:

Be it known that I, ALFRED C. URBAN, a citizen of the United States, residing at BuXTON, in the county of Monroe and State of Iowa, have invented certain new and useful Improvements in Mine-Doors, of which the following is a specification.

This invention embodies improved means of that type of operating mechanism designed particularly for opening and closing doors in entries, drifts, or passages of mines.

The main feature of the invention resides in the provision of mechanism of this class of a simplified nature which will be automatically operated by the cars approaching the door and which is particularly advantageous in that it will work successfully where located at a curve in the drift or passage, this being essential to a practical device of this kind.

For a full description of the invention and the merits thereof and also to acquire a knowledge of the details of construction of the means for effecting the result reference is to be had to the following description and accompanying drawings, in which—

Figure 1 is a top plan view of the mechanism embodying the invention, the view illustrating such mechanism arranged in a drift or passage in a mine in operable relation to the mine-door. Fig. 2 is a detail perspective view of the pressure-bar in the path of movement of the rolling-stock and which coöperates with the door-locking means. Fig. 3 is a view in elevation, showing the truck of a car in the position assumed thereby as it approaches the pressure-bar after the door or doors have been opened under the actuation of the door-opening mechanism. Fig. 4 is a view similar to Fig. 3, the truck being in engagement with the pressure-bar and the detent thrown out of operation. Fig. 5 is a detail perspective view of the shaft carrying the trip-arm and the crank-arm which connects with the door. Fig. 6 is a front elevation of the engaging member and detent, which separately coöperate with the door in holding the same open.

Corresponding and like parts are referred to in the following description and indicated in all the views of the drawings by the same reference characters.

In carrying out the invention and specifically describing the structure illustrated in the drawings, the numeral 1 indicates the

drift or passage in which the operating mechanism comprising the invention is located. This passage is provided with the usual track, the rails of which are indicated at 2, over which travel the cars which convey the mine material through such drift or passage. At 55 a suitable point in the passage 1 is located the frame 3, in which the mine door or doors are mounted, and in this instance it is preferred to provide double doors 4, horizontally or otherwise mounted in the frame 3 in such 60 a manner as to answer the purposes of the invention. A horizontal bracket 5 projects laterally from the upper portion of one of the doors 4, and a rod 6 connects this bracket with the other door, so that the doors will be 65 simultaneously operated in opening and closing. It will be obvious that either a single or double door may be used within the contemplation of the invention. The doors 4 are normally held closed by means of springs 70 75 or similar devices, such as weights or the like.

At opposite sides of the doors 4 and situated at a suitable distance therefrom in the passage 1 are mounted vertical shafts 8, carried in suitable bearings in a substantial support provided therefor. Each of the shafts 8 is provided at its upper portion with an arm 9, which extends laterally therefrom above the track 2, being arranged in the path 80 of movement of the cars which approach the mine-doors from either direction. The front portion of the car is adapted to strike the arm 9, so as to turn the shaft 8, and a crank-arm 10, projecting from said shaft 8, is operably connected with the doors 4, so that when the arm 9 of either shaft is operated by a moving car the doors will be turned open. The connections between the arms 10 and the doors 4 are indicated at 11 and 12, respectively, and said connections preferably consist of ropes or wires, one end of each of which connects directly with a door 4, the opposite end being connected with a spring 13, the latter directly attached to an arm 10. It 90 is obvious that rods or like connections may be substituted for the rope 11; but when wires or ropes are used said flexible connections pass about suitable pulleys in the length of the track. The connection 11 extends directly to the doors 4, to which it is connected, but the connection 12, which is upon the opposite side of the doors, extends beyond the 95 100 105

door-frame and about a pulley 14, and thence back again to its point of connection with the door 4, with which it coöperates, the above arrangement being necessary, so that 5 said doors 4 may be pulled open by said connection 12.

It is designed that the cars approaching the doors 4 from either direction initially actuate said doors to open the same, coöperating 10 with the arms 9 before described, and after the doors have been opened the same are held in said open position by special means which has been devised for this purpose. This last-mentioned means embodies a pressure-bar 15, which is arranged longitudinally 15 of the track at one side thereof and which is adapted to come in contact with the truck of a car as the latter approaches the same. The bar 15 is located upon one side of the doors 4 a short distance therefrom and is carried by 20 the upper ends of standards 16, pivoted at the lower extremities, as shown at 17. One of the standards 16 is connected by a link 18 with the crank-arm 19 of a shaft 20, disposed 25 adjacent the bar 15 in longitudinal alignment therewith. The shaft 20 is arranged in suitable supporting-bearings, and said shaft carries two door-holding members—namely, the engaging member 21 and a detent 30 22, pivoted to said engaging member 21. The engaging member 21 preferably consists of a wheel having a lug 23, extending therefrom and adapted to engage one of the doors 4 in order to hold the same in open position, and it will of course be understood 35 that when one door is held open the connection between the doors 4 will cause the other door to remain open also. The detent 22 consists of a dog pivoted between its ends, as 40 shown at 24, to the upper portion of the wheel of the engaging member 21, and it is preferred that this detent shall be sufficiently heavy at its lower end to hold its upper end in a position in the path of movement of the 45 door 4, with which it coöperates. A spring or like member, however, may be employed to accomplish the above purpose. When the engaging member 21 is actuated, the pivot or the detent 22 is shifted, causing the 50 latter to be disengaged from the door 4, as will be described hereinafter.

Under usual conditions of service the arms 9 will be normally held in the path of movement or travel of the cars by means of springs 55 25, connected with the crank-arms 10. As the car approaches from the direction indicated by the arrow A the front of said car will strike the arm 9 at one side of the doors 4 and force said arm toward the doors, increasing the tension of the springs 13 and operating 60 upon the connection 11, connected therewith. The provision of the springs 13 in the length of the connections 11 and 12 relieves said connections of the shock or strain which 65 would otherwise be incident to the sudden

movement of the arms 9 when actuated by a car engaging the same, the doors 4 being also relieved of shock or jar which would otherwise be incident to their opening movement. When the doors are turned open, one 70 of said doors strikes the detent 22, tilting the same and passing thereover, said detent swinging back and engaging the door, as shown most clearly in Fig. 3 of the drawings. The car-truck now engages the pressure-bar 75 15 and forces the same laterally by pivotal movement thereof, causing the arm 19 to actuate the shaft 20 in such a manner that the pivot 24 is shifted, causing the upper engaging end of said detent to be drawn beneath the door and bringing the lug 23 of the engaging member 21 into engagement with the door. The constant pressure exerted by the truck of the car against the bar 15 holds the lug 23 in engagement with the door 4, with 80 which it coöperates, and the doors are thus held open until the car or cars have passed the bar 15, whereupon the pressure against said bar being relieved the same is returned by its weight or other means to its normal position 85 in the path of travel of the cars and the lug 23 is forced toward the adjacent rail 2, and so disengaged from the door 4, permitting both doors to close simultaneously. When the car or cars approach from the opposite direction to that indicated by the arrow A, the arm 9 upon the near side of the door is actuated and the connection 12 pulled upon so as to open both doors 4, substantially in the manner described above. One of the doors 90 is engaged by the detent 22 as soon as both of the doors are open, and when the car passes through the doors the same engages the pressure-bar 15, as described above, and actuates the parts 22 and 21, and then as the car 100 moves away from the pressure-bar the latter is returned to its normal position, permitting closing of the doors in an obvious manner. 105

The member 18 may have adjustable connection with the standard 16, to which it is 110 attached, said standard being provided with a plurality of openings 16^a, through which the fastenings employed may be passed.

Having thus described the invention, what is claimed as new, and desired to be secured 115 by Letters Patent, is—

1. In operating mechanism for mine-doors, the combination of a door, means for actuating the same, a pressure-bar operable by an approaching car, a shaft, an operative connection between the shaft and the pressure-bar, a door-engaging member mounted on said shaft, a detent carried by said door-engaging member for engagement with the door, and means permitting operation of the 120 detent independently of the door-engaging member aforesaid.

2. In operating mechanism for mine-doors, the combination of a door, means for actuating the same, a door-engaging member, a de- 125 130

tent pivoted to said door-engaging member and shiftable thereby, and means for actuating the door-engaging member and this detent to effect coöperation thereof with the door.

3. In operating mechanism for mine-doors, the combination of a door, means actuating the same, a pivoted detent and means for shifting the pivot of said detent to throw the same out of coöperation with the door.

4. In operating mechanism for mine-doors, the combination of a door, means for actuating the same, a pressure-bar adapted to be

operated by an approaching car, a shaft, an operative connection between the shaft and the pressure-bar, a door-engaging member mounted on said shaft, and a detent carried by said member, said detent being adapted to coöperate to hold the door open. 15

In testimony whereof I affix my signature 20 in presence of two witnesses.
